UNITED STATES PATENT OFFICE.

ALEXANDER E. BROWN, OF CLEVELAND, OHIO, ASSIGNOR TO THE BROWN
HOISTING MACHINERY COMPANY, OF CLEVELAND, OHIO.

METHOD OF CONSTRUCTING MASTS.

No. 837,912.

Specification of Letters Patent.

Patented Dec. 11, 1906.

Application filed August 3, 1906. Serial No. 329,097.

To all whom it may concern:

Be it known that I, ALEXANDER E. BROWN, of Cleveland, in the county of Cuyahoga and State of Ohio, have invented a new and useful Method of Constructing Masts; and I hereby declare the following to be a full, clear, and exact description thereof, reference being had to the accompanying drawings, which make a part of this application.

10 While the process to be described is equally applicable to masts or stacks of any desired heights and without regard to the particular purposes their erection is to serve, it will be manifest that its greater utility will be in the construction of masts required for observation, signal, or illuminating operations, for instance, or in connection especially with space or wireless telegraphing. These purposes call for extreme heights as compared 20 with what has heretofore been realizable, except by abnormally expensive tower constructions, since the raising of masts to the elevation demanded for the best results has hitherto not been practicable.

25 It is the object and aim of the present application to point out a novel or simple mode of building up this kind of structures, and which in addition entails comparatively small expense and permits a maximum of 30 shop work, with the attending advantage of hydraulic riveting and a complete inspection of the work as it progresses.

For the purpose of illustration in the course of the explanation I am now about to 35 make I have shown and described an insulated mast or stack intended solely for use in wireless telegraphy. As above stated, however, my method of forming the mast proper is of more general application and is in no 40 sense intended to be limited to the special field of utility indicated by the drawings.

In the drawings, Figure 1 is a plan view, in diagram, of a mast or stack with sustaining-guys connected to the same and to their several anchorages, as indicated. Fig. 2 is a diagrammatic elevation of the same, showing both permanent and temporary guys, but with the front and rear guys removed. Fig. 3 is a segment or section employed in my 45 mode of constructing a mast in elevation, with the ladder preferably fixed interiorly of the same, denoted in dotted lines. Fig. 4 is a plan view of the segment shown in Fig. 3. Fig. 5 is an upright sectional view of a

portion of a mast constructed according to 55 my method through the plane of the juncture connection of any two segments thereof. Fig. 6 is a plan view of a portion of adjacent segments of said mast at the point of their juncture. Fig. 7 represents the lower part 50 of a mast constructed under and by my present method, displaying six segments or sections thereof as they figure in such construction. Fig. 8 is a view, on an enlarged scale, of one of the segments required by said method, 65 with fragmentary views of the sections in place next above and below the same and the provision for introducing within and connecting the temporary supporting-guys to said segments duly disclosed. Fig. 9 represents a portion 70 of a mast of the kind above referred to and the extremities of permanent guys attached to the same, as well as repair-balconies that may be usefully provided immediately below the same, and the temporary guys duly indicated that would probably be attached 75 to the same in the event that the connections of the permanent guys represented as immediately overhead at any time required alterations or repairs from such balconies and for 80 that reason were to be temporarily detached. Fig. 10 is an enlarged view of a form of connection of the permanent guys to the mast I produce. Fig. 11 indicates the uppermost 85 part of a stack or mast in the course of erection under my process with the form of crane I employ in position for lowering a given segment into place. Fig. 12 indicates a like view when the crane having put a given segment in place, as shown in Fig. 11, is in position to be raised to the next stage of the work. Fig. 13 is a plan view, with all tubular parts (hereinafter described) omitted therefrom, of a form of supporting-bracket that may be employed with advantage in my 90 method for the upright or vertical form of crane I use. Fig. 14 is a side view of this bracket with portions of the tubular-connection features indicated which in one form or another are used. Fig. 15 is a side view of 100 the parts shown in Fig. 13, but with the fastening-bolt, that is projected in said figure, thrust backwardly (as signified by dotted line) within a housing provided for the purpose; and Fig. 16 is a sectional view on the 105 lines X X of Fig. 14.

In the several figures the same parts are denoted by the same referential letters.

M is the mast proper in place, and G G' G², G³ permanent guys for the same, and g, g', g², g³, and g⁴ those used for temporary supporting purposes at the various stages of the erection. The anchorages A A for these guys as laid out in the drawings are arranged around the site of the mast in twos at the several quadrant-points in radial relation to each other. They may be constructed in any manner deemed best suited to their functions.

F indicates a frame for the transmitting-wires employed, which may also take any form that is considered best adapted to its purpose.

B B are repair-balconies for the guy connections, and as such are of course severally located at various points on the mast M immediately beneath the permanent guys G G' G² G³, &c. Said guys themselves in the drawings herewith are made of a series of lengths of steel cable insulatively linked together and connected at one end of the series to the mast and at the other end to their several anchors. While any appropriate form of insulated connection is open for use, in the illustrations of the particular kind of mast herein shown the special form of such connection illustrated in Fig. 10 is considered especially efficient and as such as being proper to be reserved by me as the subject of a separate application.

S S represent the several segments of which the mast M is composed. They are cylindrically shaped of sheet-steel and they have equal dimensions one with respect to the other, except the lowermost segment, which, preferably, as is shown, is shorter than the others. At suitable distances above the lower edge of said segments are apertures or crane-holes h for the reception at the same time of the bolts b of the double brackets d and the handle H of the worm-gear arrangement w, which is provided for revolving the crane C, as hereinafter explained. At points where the mast M is to be temporarily guyed during its construction the several segments S should be provided with other apertures or holes h', equidistantly spaced around the same, for the reception of the extremities of said guys and in such relation with respect to the apertures or crane-holes h as will leave an open passage-way between the guys for the upward hoist of the segments to their several placements. Bearing-blocks may be usefully laid behind said guy-holes, as is indicated in dotted lines and by v'.

D is a form of double bracket I provide to serve as a sort of socket-support for the crane's standard during the process of assembling the several segments S into the mast M. It is provided with a base or support l, with legs or contact-bearings l', that conform to the outer circumferential configuration of the segments themselves. Said brackets pro-

ject outwardly from said base into a sleeve-bearing m of suitable dimensions to receive a fixed tubular connection n within the same. The upper and lower members of the bracket D are denoted by d. They each contain longitudinal recesses that serve as housings for a sliding bolt b, which bolt is threaded at its inner or projective end to receive a hand-nut f. The sliding bolts b are provided with heads e, whereby their reciprocal movements outwardly of their housings will be stopped when such heads bring up against the guide-pieces or stops i in said housings provided for the purpose. These guide-pieces are located at such points in their respective housings as will limit the outward reciprocation of the bolts b and enable the bracket parts d to be brought firmly into bearing against the segments S when the hand-nuts f are screwed home against the washers v.

C is a crane. It is composed of a fixed frame k, carrying sheaves s s', and a tubular post or standard r, which latter is so related to the frame k and the sheaves s s', carried thereby, that its bore will always be in vertical alinement with the bore of said sheaves. t is a hoisting-rope reeved around said sheaves and having the strands thereof that are to be connected with the source of power passing downwardly from the sheave s' into and through the bore of the post or standard r. The hoisting end of said rope is shown as carrying a bail b', the forks of which are spread to span the annular connecting-block N and to be bolted or otherwise attached thereto when said blocks are in place within their respective segments, as hereinafter explained.

To the inner end of the frame k is attached a chain-hoist p in operative connection with a guiding-beam O for the purpose of raising and lowering the same. This guiding-beam at one end embraces the post r of the crane C as a sliding sleeve or collar and extends horizontally therefrom to a suitable distance to overlap the top of the mast M at each stage of its construction when revolved about the same, and the crane C is in the described place for such movement. The under side of the beam O carries a hoisting-tackle J, adapted to hook on and raise the double bracket D. Said beam is otherwise provided with bolts j at suitable points to enable it to thereby become bolted across the top of a segment S through the bolt-holes of the annular connecting-blocks N. The blocks N and N' are annular steel castings of proper dimensions to fit into the segments S S at their ends. They have interior flanges around each edge, duly provided with bolt-holes throughout their extent. Said blocks are firmly riveted in their respective places within the segments S. As shown in Fig. 5, I have made the block N', which is to occupy the lower end of a given segment when raised to its place in the mast, 130

with a downwardly - extending centering flange *u* around its lower edge.

H' represents rod-bolts passing through the blocks *N N'* of contiguous segments, and 5 thereby locking them in place.

w indicates a worm-gear arrangement for revolving the tubular post *r* through the hand-wheel *w'*.

Having explained the several parts employed in said method, the operation itself by which they are utilized is substantially as follows, namely: The segments *S*, having been made in the shop with the blocks *N* and *N'* duly riveted into the same, as pointed out, 15 the three segments *S* are bolted together at the site of the mast and raised into place. Temporary guys may now be added (and from time to time thereafter as the work progresses) by passing the mast ends of such 20 guys through the guy-holes *h'* and over the bearing-block *v'* down to rod-bolts *H'* in the connecting-blocks *N'*, where the same may be secured very conveniently to the bolts themselves by, for instance, removing a top nut in 25 each case and substituting therefor a specially prepared clevis-nut, with which the guy-rope may be connected. The crane *C* is next attached in its upright operative position by bolting the bracket members *d* of the double 30 bracket *D* (carrying the crane) through the crane-holes *h* of the adjacent segments *S*. A fourth segment may now be brought up by means of said crane, and when its load has been hoisted above the level or plane of its 35 place said crane is revolved one hundred and eighty degrees by means of the worm-gear arrangement *w* until the segment is above said place, when the latter is immediately lowered into position and secured to the stack by the 40 rod-bolts *H'*. The crane is thereupon revolved to its former position, which will bring the beam *O* above the segment just placed and in position to be bolted to the same through the bolt-holes in the connecting-block 45 *N*. Under these conditions the bolts *b* of the bracket parts *d* can be unloosed and the double bracket *D* hoisted by the tackle *J* until said bolts are in front, respectively, of the crane-holes *h* in the fourth and fifth segments, to which the bracket *D* is attached, as 50 before. The crane *C* by this operation is of course carried upwardly a corresponding distance and in position to elevate a sixth segment to its place as soon as the beam *O* is 55 loosened and raised by the chain-hoist *p*. The

operation just described is of course to be repeated until each segment required for the mast's construction has been thereby brought to and secured in its proper place in the series.

Having thus described my invention, what 60 I claim, and desire to secure by Letters Patent, is—

1. The process of constructing masts of sheet metal or similar material, by first forming the material into cylindrical segments, 65 with holes for crane-bolts therein, and annular connecting-blocks at each end, and, thereafter, successively superimposing such segments, one upon another, to constitute the mast, by hoisting them by means of a crane 70 which is bolted to the work in progress, in operative position to deliver a segment above the same, and, which, after the delivering and permanent fixing of a given segment in place, is itself raised to a position for delivering the 75 next segment, by first temporarily fastening a guiding-beam to said work, to sustain the crane during the operation, and, then, unbolt- 80 ing the crane from said work; and causing power to be applied to a hoisting apparatus connecting the beam and crane, until the latter is brought to the new position where it is secured as before.

2. The process of constructing masts of sheet metal, or similar material, by first, 85 forming the material into cylindrical segments, with holes therein, suitably spaced, for temporary guy-ropes, and, holes for crane-bolts, and, also, annular connecting-blocks riveted, within the same at each end, and, 90 thereafter, successively superimposing such segments, one upon another, to constitute the mast, by hoisting them by means of a crane which is bolted to the work, in progress, in operative position to deliver its load above 95 the same, and which is, itself, raised to new positions for operation, by first temporarily fastening a guiding-beam, provided for the purpose, across the top of said work, to sustain said crane, while being so raised, and, 100 then, unbolting the same from the work, and causing power to be applied to a hoisting apparatus connecting the beam and crane, until the latter is brought to the new position where it is secured as before.

ALEXANDER E. BROWN.

In presence of—

A. M. MERRYWEATHER,
RICHARD B. SHERIDAN.
